Joaquin Vincent Torras, Staten Island, N. Y.

This invention relates to improvements in container for foods and beverages, especially the type made of all metal or metal ends.

Containers of this type usually comprise one having flat ends and another having a spout. In the flat type which can be easily stacked for display, shipping or storage purposes, it requires the puncturing of one end to provide an outlet or dispensing means to withdraw the contents.

10 Although satisfactory for stacking purposes, these flat end containers are unsanitary and cause difficulties in pouring, and once punctured cannot be closed again. For this reason the container with a spout is preferable and becoming more 15 popular. It is with this spout type of can this invention is concerned.

The spout type of container is, however, difficult to stack for shipping, display and other purposes, as the crown or screw cap closure does not provide a satisfactory base upon which to rest the next can.

The present invention overcomes these and other difficulties.

It is an object of this invention to provide a
25 container made of metal or other suitable mate-
rial with a bottom, which will fit over the top of
an adjacent aligned similar container, thereby per-
mitting the rims of the two containers to contact
and to give a secure resting surface.

30 It is another object of this invention to provide
in a container a recessed bottom which will fit
closely over the crown or screw cap closure of a
preceding similar container, thereby preventing
any shifting of the containers in relation to each
35 other when the containers are stacked while, at
the same time, maintaining the rigidity of the
bottom against weakening thereof, or of its
seamed joint with the wall of the container.

It is a still further object of this invention to provide the container tops with corrugations, as projections, which will coincide with depressions in the bottom of the adjacent aligned cans, thereby preventing the rotation of the various stacked containers in relation to each other.

45 To enable others skilled in the art so fully to comprehend the underlying features thereof that they may embody the same by the numerous modifications in structure and relation contemplated by this invention, a drawing depicting
50 certain forms of the invention has been annexed as a part of this disclosure, and in such drawing, like characters of reference denote corresponding parts throughout all the views, of which:—

Fig. 1 represents a side elevational view, half 55 in section, of two aligned similar containers in

Cl. 220—97)

Fig. 2 shows a partly sectioned and partly broken away.

Fig. 2 shows a partly sectional and partly broken away, view of the invention in a modified form in which the container bottom is provided with projections to register with corresponding depressions on the top of a similar container. 5

The drawing shows examples of how the invention may be applied.

The container 10 may have the conventional cylindrical shell or wall comprising the body 11 and top 13, and further has a substantially annular bottom 12. The bottom 12 and the top 13 may be secured at opposite ends to body 11 in the conventional manner of seam construction 14 providing a rim 20 on bottom 12 and a rim 21 on top 13. The top 13 of the container comprises the substantially frustro-conical wall forming shoulder S and a substantially cylindrical wall protruding from shoulder S forming a neck or spout 15. Spout 15 may be closed in the conventional manner by means of a crown cap 16 or screw cap (not shown) in the latter case threads being provided on the spout 15 for interengagement with those on the cap. 25

Bottom 12 may be provided with a recess 17 defined by wall W (Fig. 1), or a recess 17' defined by wall W' (Fig. 2), or any other suitable wall for the purpose intended.

These walls, W, W', are formed such that the recesses 11, 17', will house that portion of top 13 which protrudes above rim 21 of a companion stacked container. The bottom 12 or 12' extends downwardly from the seam 14 in an inverted conical portion, terminating in an upwardly extending conical portion 18, complementary with the conical top 13. These walls therefore act as reinforcing means for the bottom of the container and prevent opening of the seamed joint thereof. In recess 17 defined by wall W, the angular portion 18 of the latter is adapted to rest against the portion 19 of shoulder S of a similar container.

Figure 1 shows two adjacently aligned or stacked similar containers wherein the bottom rim 20 of the upper container rests on the top rim 21 of the lower container and portion 18 of wall W rests on portion 19 of shoulder S. The cap 16 is within the cylindrical portion 30 of wall W which extends from portion 18 and which is the deepest portion of recess 17. Portion 22 of recess 17 provides a clearance for cap 16. 45 50

In the arrangement illustrated in Fig. 2, the wall **W'** of bottom **12'** is provided with projections **23** which are adapted to fit into depressions **24** of the top **13'** of a similar container. The 55

edges or rims 20 and 21 will also contact in this case.

Although I have here shown the application of my invention to a cylindrical container it is 5 understood that the same is applicable to any type of container of the spout class.

I desire it understood that the invention is not to be confined to the particular forms shown and described, the same being merely illustrative, 10 and that the invention can be carried out in other ways without departing from the spirit thereof, and therefore, I claim broadly the right to employ all equivalent instrumentalities coming within the scope of the appended claims, and 15 by means of which objects of my invention are attained and new results accomplished, as it is obvious that the particular embodiments herein shown and described are only some of many that can be employed to attain these objects and accomplish these results.

Having described my invention, what I claim as new, and desire to secure by Letters Patent, is:

1. A container comprising a wall having top and bottom attached thereto by seamed joints 20 extending inwardly of the extreme ends of said 25

wall providing end rims thereon, the top rising in frustro-conical shape from its seamed juncture with the wall, and the bottom having an inverted conical portion extending from the seamed joint and terminating in an upwardly extending conical portion complementary with the frustro-conical top to fit on the top of a similar container stacked therewith.

2. A container comprising a wall having top and bottom attached thereto by seamed joints 10 extending inwardly of the extreme ends of said wall providing end rims thereon for stacking a plurality of said containers, the top rising in frustro-conical shape from its seamed juncture with the wall with a neck at its upper end, and the bottom having an inverted conical portion extending from the seamed joint and terminating in an upwardly extending conical portion complementary with the frustro-conical top to fit on the top of a similar container stacked therewith, said upwardly extending conical portion having a cylindrical portion at the upper end thereof to enclose the neck of the stacked container.

JOAQUIN VINCENT TORRAS. 25
